UNITED STATES PATENT OFFICE.

RALPH G. PACKARD, JR., OF MORRISTOWN, NEW JERSEY.

DETACHABLE SIGHT FOR RIFLES.

Application filed May 31, 1927. Serial No. 195,358.

My present invention relates more particularly to telescopic sights for rifles, and while its novel features are of particular importance in connection with high power rifles, 5 they will also be useful on any rifle where a telescope sight is desired. Specifically considered, it contemplates improved means for embodying many of the broad principles set forth in my application Ser. No. 661,559, 10 filed September 8, 1923, now Patent No. 1,656,496, granted January 17, 1928.

As explained in said prior application, the telescope is rigidly and non-adjustably secured on a mounting frame, and the mounting 15 is rigidly and non-adjustably but detachably secured to the frame of the rifle, the necessary zeroing for elevation and drift, as also the field adjustments for range and windage, being accomplished by specially designed 20 means for vertical and lateral adjustment of a sighting reticule located within the telescope.

An important feature is novel means for detachably securing the telescope to its mount 25 and locking the mount to the rifle so rigidly that shift of the telescope relative to the rifle is impossible and the telescope and its mount will recoil with the gun as if it were all one piece.

50 My present invention includes improved means for applying the great power necessary for thus forcing devices, such as the relatively steep angle wedge lugs disclosed in said patent, to locked position and for setting up and maintaining the extreme elastic stress necessary to hold them there against recoil and counter-recoil.

The telescope is located in what may be 40 called binocular relation to the regular iron sights and is clamped to a detachable mount which may be forced longitudinally of the gun barrel into close locking relation with a frame permanently fixed to the gun. To effect such wedging according to the present invention, a carriage is mounted to slide in the mount longitudinally of the gun and has a part projecting into a suitable opening in the frame on the gun.

Pivoted on the carriage at the outer side 50 is a cam or eccentric which fits in an opening on a carriage slidable at right angles to the direction of movement of the first carriage and the clamping of the mounting on the gun is effected by turning the eccentric. 55 Preferably such turning of the eccentric is done by an arm having a vernier connection

with the head of the eccentric so that the lever can be adjusted closely with reference to the head of the eccentric and when it reaches a definite fixed position, the eccentric will be 60 fully effective.

To provide for greater exertion of pressure in the final movement of the cam or eccentric, said arm has pivoted thereto at its free end a lever with a relatively long, somewhat flexible, operating arm and a short work arm which may be engaged with one side of a recess into which it passes when the clamping is effected. Locking of the two levers in clamping position may be effected in any 70 suitable manner as for example by a catch which may be released by springing or bending the power arm of the second lever.

It will be evident that by use of the apparatus of the present invention very great 75 clamping force may be exerted and at the same time the clamping may be effected or relieved easily and quickly. It should also be noted that due to the provision of the second slidable carriage the side thrust on the 80 mounting will be materially reduced.

The above and other features of my invention may be more fully understood from the following description in connection with the accompanying drawings, in which 85

Fig. 1 is a side elevation of the telescope and mount as applied to the left side of the rifle;

Fig. 2 is a top plan view of the telescope and mount in position on the frame of the 90 rifle;

Fig. 3 is a section on the line 3—3 of Fig. 1;

Fig. 4 is a rear view of the structure shown in Fig. 3;

Fig. 5 is a side elevation of the receiver 95 frame showing the recesses for engagement by the telescope mount;

Fig. 6 is a sectional view taken along the line 6—6 of Fig. 2;

Fig. 7 is a sectional view taken along the 100 line 7—7 of Fig. 2; and

Fig. 8 is a section on the line 8—8 of Fig. 5.

In Fig. 1 my telescope sight is shown as applied to a rifle comprising stock 1, receiver frame 2, and barrel 3 which may be provided 105 with usual iron sights. As indicated more clearly in Fig. 2, I have selected for the purpose of illustration a gun designed by me which is more fully shown and described in my Patent No. 1,582,533, granted April 27, 110 1926, the peculiarities of which are not essential to my present invention and need be

mentioned only to the extent of identifying rear sight 5, breech bolt 6, operating lever 7, down-pressure safety release 8, down-pressure thumb trigger 9, and bolt releasing member 10. In this particular case the receiver frame, as shown in Fig. 5, is specially designed for detachably securing my telescope mount, but it will be evident that the proportions and disposition of the locking elements may be varied, to suit the frames of particular guns and it is almost always possible to braze to any gun frame a plate having the desired locking recesses either modified or, if desired, in the exact form shown in the drawings.

As shown in Fig. 1, the detachable carriage or mount for the telescope comprises a relatively long rigid frame or bar 11, having preferably integral therewith upward extending front and rear bracket members 12 and 13 respectively, terminating at their upper ends in semicylindrical seats in which the telescope is held by ring clamps 14 and 14^a adapted to encircle the front and rear ends respectively of telescope tube 15. In each clamp the central portion, extending somewhat more than a semicircle, is a relatively springy, band-like member of great tensile strength, while the end portions 14^e, 14^a are progressively thicker and more rigid toward the ends and are interiorly formed to fit the curved exterior of the bracket members. The design is such that by operating screw means, such as bolts 16 and nuts 17, the ring clamps may be tightened on the telescope tube with almost any desired pressure. The free ends first engage the seats and as the nut is tightened, the rigid end portion operates as a lever of the second class and also sliding wedge or cam element capable of tightening the band to apply clamping stress up to the limit of strength of the parts. To further prevent possibility of endwise shift of the telescope, its rear end is provided with an exterior lug 15^b, which, as shown in Fig. 1, has a forwardly presented radial face abutting squarely against the rear face of bracket 13, thereby applying the recoil of the rifle directly to the telescope and relieving the ring clamps 14, 14^a of all stress except the endwise tension required for clamping the telescope to the bracket seats.

The bar 11 is provided on its frame engaging face with pairs of undercut guide lugs 18, 18, Figs. 2 and 7, at the rear, and 19, 19, Figs. 2 and 6, at the front adapted to engage undercut recesses in the frame, Fig. 5. Preferably, the outwardly presented side 20 of each projection is beveled so the projections cooperate for dovetail fit and simple sliding engagement with the corresponding undercut surfaces 22 in the frame. Preferably, these surfaces are parallel in direction of slide so as to wedge only upon outward stress. Inward wedging under endwise stress is effected

by providing the lugs 18, 18, with forwardly presented wedge surfaces 23 which abut directly against the transversely disposed wedge surfaces 24 in the frame. The effective wedging angle of these surfaces 23, 24, is 70 very steep, as will be evident from Fig. 8, where the wedging angle actually shown is about 60 degrees.

The top and bottom undercut guide surfaces 20, 22, are simply close fitting slide surfaces, preferably parallel with the axis of the barrel, their length of slide being made great enough to permit the transverse wedge surfaces 23, 23, to contact with the transversely disposed wedge surfaces 24, 24, substantially 80 before the forward lugs approach the ends of their slide recesses. The longitudinal slide recesses on the frame are cut away as at 25, 25, for the rear lugs or projections and 26, 26, for the forward lugs so that all of said lugs 85 may be laterally applied to or removed from the frame through the corresponding cut-away portions.

In this preferred design of locking lugs and recesses, all forward stress on the mount such as result from recoil of the gun, take effect solely on wedge surfaces 23, and as these surfaces have a steep wedging angle, a most rigid locking engagement may be had by very slight forward movement of the telescope mount 90 and as before explained, the means for effecting this movement may have a correspondingly great motion-reducing, power-multiplying ratio for easily applying and maintaining great stress. As seen in Figs. 1, 3 and 4, the member or block that applies the thrust against the receiver frame of the gun, consists of a rearward projection 27 from a plate or member 28 slidable in a slot 29 at the rear face of said bar 11. Said projection 27 is 100 substantially in the shape of a rectangular box adapted to project into recess 30 in the receiver frame 2. The end 27^a of this box has a long surface bearing for thrust engagement with the wall 30^a of recess 30, which is 110 in a plane at right angles to and in the line of slide of the mount. The member or carriage 28 is provided with a forwardly projecting boss 29^a in which is mounted an eccentric 30^a which in turn is rotatably mounted in a slide block or carriage 31, guided up and down in a slot 32 at the front of the member 11. Said eccentric 30^a may be held in position on the boss 29^a by means of a screw 33 threaded into the boss 29^a. The eccentric 120 30^a is provided with a series of openings 34 to enable the annular end of an arm or lever 35 to be adjustably secured to the eccentric by screws 36 passing through openings 37 in the annular portion of the lever 35 and threaded into vernier openings 34 of the eccentric. A very fine adjustment is necessary at this point, because the final locking movement is extremely small and because the positive, exact opposition of the stresses must be accommo- 125 130

dated by the elasticity of the steel of the clamping mechanism, the range of which is short by reason of its structural strength. To permit the locking mechanism to reach locking position within this small range of movement, openings 37 and 34 are arranged in vernier relation to enable extremely fine adjustment between the lever 35 and the eccentric 30^a as will be described more fully hereinafter.

As shown in Fig. 1, the lever 35 is in locking position and the eccentric 30^a exerts pressure to the left against the slide block 31 and consequently against the member 11, and the member 27 exerts pressure to the right against surface 30^a of the receiver frame 2. In this arrangement, it will be seen that the eccentric does not act directly against either the receiver frame 2 or the member 11 but moves up and down to adjust itself in relation to the position of the member 27, the movement of which latter is limited to sliding movement parallel with the axis of the rifle barrel. The movement of the member 35 to locking position is effected by means of a second lever 38 pivoted at 39 at the end of the lever 35 and having a rounded end 39^a extending into an opening 40 in the bracket 12 between two webs 41. At its end opposite the rounded portion 39^a, the lever 38 is provided with upper and lower finger pieces 41^a to facilitate the shifting thereof and with an end lug finger 42 to seat in a locking recess 42^a at the lower side of a stop lug 43 when the lever 35 is brought to its locking position. It will be apparent that as a result of the use of the lever 38 in connection with the lever 35 a very strong wedging or camming action can be obtained.

To remove the member 11 from the rifle, the user grasps the finger pieces 41^a and withdraws the lug 42 from the notch or recess 42^a and swings downwardly the lever 38, thereby forcing down the right end of lever 35 and releasing the member 11 so that it may be slid rearwardly and removed laterally. It should be noted that the upper wall of the opening 40 extends farther to the front than the lower wall, thus aiding in moving the lever 38 free of said opening 40.

In this operation, the lever 38 swings about the pivot 39 until it comes into engagement with a stop 35^a on lever 35 and then the two levers may move as one to the dot-and-dash positions shown in Fig. 1.

The proper relation between the lever 35 and the eccentric 30^a, as required for properly stressing the elasticity of the parts, may be obtained by removing the screws 36, bringing two diametrically opposite vernier openings 37 in register with two suitably positioned vernier openings 34 of the eccentric, passing the screws 36 through the selected openings 37 to engage in the corresponding openings 34, and tightening the screws to maintain the adjustment. If, as shown, the

number of openings 37 is 18 and there are 20 openings 34, the adjustment may be made to one one hundred-eightieth of a complete revolution

$$\left(\frac{1}{18 \times 10} \right)$$

70

or two degrees.

It will be noted that while the telescope is thus removable and replaceable, it is functionally an integral part of the rifle frame which cannot be adjusted either vertically or laterally. While vertically adjustable sights within the telescope offer no particular problem and are well known, it is obvious that for careful, accurate shooting, which the necessity for a telescope presupposes, lateral adjustment for windage, at the will of the user, is highly desirable and that some form of adjustable or permanent accommodation for zeroing and drift of the bullet is absolutely essential. My present telescope, which is disclosed and claimed specifically in my co-pending application Serial No. 195,357, filed May 31, 1927, provides very reliable, accurately adjustable means for effecting each of these adjustments.

It should be understood that the telescope may be of any suitable form. The form illustrated has, however, particularly advantageous features and is fully disclosed in my co-pending application Serial No. 195,357, filed May 31, 1927.

I claim:

1. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the gun frame, in combination with camming means interposed between thrust surfaces on said frame member and said gun frame respectively to force said wedging surfaces into locking engagement and including a rotatable part for making the same effective, and actuating means for said camming means including an arm swingable to a definite locking position, means to lock said arm in said locking position, and means for adjusting said arm with reference to said rotatable part, including a vernier arrangement of openings in said arm and said rotatable part adapted to have holes in register at two diametrically opposite points and fastening devices inserted in said openings.

2. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting corre-

- spondingly shaped recesses on the gun frame, in combination with camming means interposed between thrust surfaces on said frame member and said gun frame respectively to 5 force said wedging surfaces into locking engagement and including a rotatable part for making the same effective, and actuating means for said camming means including a pivotally mounted arm attached to said rotatable part and movable to a definite locking position lengthwise of the gun and having a recess in one of its lateral faces, and a lever pivoted on said arm and slidably fulcrumed on said frame member, and having 10 at its free end a projection to snap into said recess and lock said arm and lever in effective positions. 70
3. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the gun frame, in combination with a camming means interposed between thrust surfaces on said frame member and said gun frame respectively and including a rotatable part for 75 making the same effective, and actuating means for said camming means including a pivotally mounted arm attached to said rotatable part and movable to a definite locking position extending lengthwise of the gun, a lever pivoted on said arm and slidably fulcrumed on said frame member to move said arm to locking position, and snap locking means for holding said arm and said lever in locking position including cooperating parts on said arm and lever. 80
6. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the frame, in 85 combination with a carriage fitting in a recess on the frame and bearing upon a thrust surface of said recess and guided for sliding lengthwise on said frame member, and power multiplying means for forcing said frame member along said dovetail and said vertically extending wedging surfaces into intimate engagement with the corresponding wedge recesses on the frame, said power multiplying means being interposed between said carriage and said frame member and including an eccentric pivoted on said carriage, a second carriage slideable on said frame member transversely of the path of the first mentioned carriage and in which said eccentric is rotatably mounted, and means to 90 rotate said eccentric. 100
4. A gun including barrel, frame, stock and firing mechanism, in combination with a sighting telescope and means for detachably mounting it on the gun, including a rigid bar or frame member having an undercut wedging surface extending vertically at right angles to the axis of the barrel and a dovetail extending lengthwise of said axis, both fitting correspondingly shaped recesses on the gun frame, in combination with camming means interposed between thrust surfaces on said frame member and said gun frame respectively and including a rotatable part for making the same effective, and actuating means for said camming means including a pivotally mounted arm attached to said rotatable part and movable to a definite locking position extending lengthwise of the gun, a lever pivoted on said arm and slidably fulcrumed on said frame member to move said arm to locking position, and snap locking means for holding said arm and said lever in locking position. 110
5. Means for detachably mounting a sight 115
- ing telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the gun frame, in combination with a camming means interposed between thrust surfaces on said frame member and said gun frame respectively and including a rotatable part for making the same effective, and actuating means for said camming means including a pivotally mounted arm attached to said rotatable part and movable to a definite locking position extending lengthwise of the gun, a lever pivoted on said arm and slidably fulcrumed on said frame member to move said arm to locking position, and snap locking means for holding said arm and said lever in locking position including cooperating parts on said arm and lever. 120
7. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the frame, in 125 combination with a carriage fitting in a recess on the frame and bearing upon a thrust surface of said recess and guided for sliding lengthwise on said frame member and power multiplying means for forcing said frame member along said dovetail and said vertically extending wedging surfaces into intimate engagement with the corresponding wedge recesses on the frame, said power multiplying means being interposed between said carriage and said frame member and including an eccentric pivoted on said carriage, a second carriage slideable on said frame member transversely of the path of the first mentioned carriage and in which said eccentric is rotatably mounted, and means to rotate said eccentric. 130

50

1,704,060

5

- carriage and said frame member and including an eccentric on said carriage, a second carriage slidable on said frame member transversely of the path of the first mentioned carriage and in which said eccentric is rotatably mounted, and means to rotate said eccentric, including an arm shiftable to and from locking position and an adjustable connection between said eccentric and said arm. 5
10. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the frame, in combination with a carriage fitting in a recess on the gun and bearing upon a thrust surface of said recess 70 and guided for sliding lengthwise on said frame member, and power multiplying means for forcing said frame member along said dovetail and said vertically extending wedging surfaces into intimate engagement with the corresponding wedge recesses on the frame, said power multiplying means being 75 interposed between said carriage and said frame member and including an eccentric, a member pivoted on said carriage, a second carriage slidable on said frame member transversely of the path of the first mentioned carriage and in which said eccentric is rotatably mounted, and means to rotate said eccentric including an arm connected therewith and having a locking recess, a lever pivoted intermediate its ends on said arm and having at 80 one end a projection to enter said recess and hold said arm in locking position and at the other end a portion adapted to be slidably fulcrumed between two parallel bearing surfaces on said frame member. 85
15. The barrel and a dovetail extending lengthwise of said axis, both fitting correspondingly shaped recesses on the frame, in combination with a carriage fitting in a recess on the gun and bearing upon a thrust surface of said recess 90 and guided for sliding lengthwise on said frame member, and power multiplying means for forcing said frame member along said dovetail and said vertically extending wedging surfaces into intimate engagement with the corresponding wedge recesses on the frame, said power multiplying means being 95 interposed between said carriage and said frame member and including an eccentric pivoted on said carriage, a second carriage slidable on said frame member transversely of the path of the first mentioned carriage and in which said eccentric is rotatably mounted, and means to rotate said eccentric including an arm connected therewith and having a locking recess, a lever pivoted intermediate its ends on said arm and having at 100 one end a projection to enter said recess and hold said arm in locking position and at the other end a portion adapted to be slidably fulcrumed between two parallel bearing surfaces on said frame member. 100
20. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the frame, in combination with a carriage fitting in a recess on the gun and bearing upon a thrust surface of said recess 105 and guided for sliding lengthwise on said frame member, and power multiplying means for forcing said frame member along said dovetail and said vertically extending wedging surfaces into intimate engagement with the corresponding wedge recesses on the frame, said power multiplying means being 110 interposed between said carriage and said frame member and including an eccentric pivoted on said carriage, a second carriage slidable on said frame member transversely of the path of the first mentioned carriage and in which said eccentric is rotatably mounted, and means to rotate said eccentric including an arm connected therewith and having a locking recess, a lever pivoted intermediate its ends on said arm and having at 115 one end a projection to enter said recess and hold said arm in locking position and at the other end a portion adapted to be slidably fulcrumed between two parallel bearing surfaces on said frame member. 115
25. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the frame, in combination with a carriage fitting in a recess on the gun and bearing upon a thrust surface of said recess 120 and guided for sliding lengthwise on said frame member, and power multiplying means for forcing said frame member along said dovetail and said vertically extending wedging surfaces into intimate engagement with the corresponding wedge recesses on the frame, said power multiplying means being 125 interposed between said carriage and said frame member and including an eccentric pivoted on said carriage, a second carriage slidable on said frame member transversely of the path of the first mentioned carriage and in which said eccentric is rotatably mounted, and means to rotate said eccentric including an arm adjustably connected with said eccentric, a lever pivoted intermediate its ends on said arm and having a rounded end adapted to slide between two parallel surfaces on said frame, the upper of said surfaces extending farther to the front than the 130 eccentric, and a lever pivoted on said arm and

lower so that the fulcrum end of the lever may pass downwardly at the forward end of said lower surface, means to lock said lever to said arm and hold it in locking position, and 5 means to limit the pivotal movement of said lever relative to said arm.

12. Means for detachably mounting a sighting telescope on a gun having a barrel, frame and stock, including a rigid bar or 10 frame member having an undercut wedging surface extending vertically at right angles to the axis of the barrel and a dovetail extending lengthwise of said axis, both fitting correspondingly shaped recesses on the frame, 15 in combination with a carriage fitting in a recess on the frame and bearing upon a thrust surface of said recess and guided for sliding lengthwise on said frame member, and power multiplying means for forcing said frame 20 member along said dovetail and said vertically extending wedging surfaces into intimate engagement with the corresponding wedge recesses on the frame, said power multiplying means being interposed between 25 said carriage and said frame member and including an eccentric pivoted on said carriage, a second carriage slideable on said frame member transversely of the path of the first mentioned carriage and in which said eccentric is 30 rotatably mounted, and means to rotate said eccentric, including an arm shiftable to and from locking position and an adjustable connection between said disc and said arm including locking screws engaging circularly 35 arranged recesses in vernier relation, in said disc and arm respectively.

13. Means for detachably mounting a sighting telescope on a gun having a barrel, frame and stock, including a rigid bar or 40 frame member having an undercut wedging surface extending vertically at right angles to the axis of the barrel and a dovetail extending lengthwise of said axis, both fitting correspondingly shaped recesses on the frame, 45 in combination with a carriage fitting in a recess on the frame and bearing upon a thrust surface of said recess and guided for sliding lengthwise on said frame member, and power multiplying means for forcing said frame 50 member along said dovetail and said vertically extending wedging surfaces into intimate engagement with the corresponding wedge recesses on the frame, said power multiplying means being interposed between 55 said carriage and said frame member and including an eccentric pivoted on said carriage, a second carriage slideable on said frame member transversely of the path of the first mentioned carriage and in which said eccentric is 60 rotatably mounted, means to rotate said eccentric, including an arm connected therewith and a lever pivoted on said arm and having one end adapted to be slidably fulcrumed on said frame and its other end adapted to have a snap locking engagement with said 65 arm, and means to lock said lever to said arm when the

latter is in effective position, including a recess in one of these members and a projection on the other adapted to engage said recess.

14. A gun including barrel, frame, stock and firing mechanism, in combination with a 70 sighting telescope and means for detachably mounting it on the gun, including a rigid bar or frame member having an undercut wedging surface extending vertically at right angles to the axis of the barrel and a dovetail 75 extending lengthwise of said axis, both fitting correspondingly shaped recesses on the frame, in combination with a carriage fitting in a recess on the frame and bearing upon a thrust surface of said recess and guided for 80 sliding lengthwise on said frame member, and power multiplying means for forcing said frame member along said dovetail and said vertically extending wedging surfaces into intimate engagement with the corresponding wedge recesses on the frame, said power multiplying means being interposed between said carriage and said frame member and including a cam member pivoted on said carriage, a second carriage vertically 85 slideable on said frame member and interposed between said cam and said frame member, and means for actuating said cam.

15. Means for detachably mounting a sighting telescope on a gun having a barrel, 90 frame and stock, including a rigid bar or frame member having an undercut wedging surface extending vertically at right angles to the axis of the barrel and a dovetail extending lengthwise of said axis, both fitting correspondingly shaped recesses on the frame, in 95 combination with a carriage bearing upon a thrust surface in a recess of said frame slideable lengthwise in said frame, and power multiplying means for forcing said frame member along said dovetail and said vertically extending wedging surfaces into intimate engagement with the corresponding wedge recesses on the frame, said power multiplying means being interposed between said carriage 100 and said frame member and including an eccentric pivoted on said carriage, a carriage for said eccentric slideable on said frame member transversely of the path of the first mentioned carriage, means to rotate said eccentric, including an arm attached to said eccentric and a lever pivoted on said arm and having one end adapted to be slidably fulcrumed on said frame and its other end adapted to have a snap locking engagement with said 110 arm.

16. Means for detachably mounting a sighting telescope on a gun having a barrel, frame and stock, including a rigid bar or frame member having an undercut wedging surface extending vertically at right angles to the axis of the barrel and a dovetail extending lengthwise of said axis, both fitting correspondingly shaped recesses on the gun frame, 125 in combination with camming means carried 130

- by said frame member and interposed between thrust surfaces on said frame member and said gun frame respectively to force said wedging surfaces into locking engagement 20
5 and including a rotatable part for making the same effective, and actuating means for said camming means including an arm swingable to a definite locking position and means to lock said arm in said locking position.
10 17. Means for detachably mounting a sighting telescope on a gun having a barrel, frame and stock, including a rigid bar or frame member having an undercut wedging surface extending vertically at right angles 30
15 to the axis of the barrel and a dovetail extending lengthwise of said axis, both fitting correspondingly shaped recesses on the gun frame, in combination with camming means 35 carried by said frame member and interposed between thrust surfaces on said frame member and said gun frame respectively to force said wedging surfaces into locking engagement and including a rotatable part for making the same effective, and actuating means for said camming means including an arm swingable to a definite locking position, means to lock said arm in said locking position, and means for adjusting said arm with reference to said rotatable part including a vernier arrangement of openings 30 in said arm and said rotatable part adapted to have holes in register at two diametrically opposite points and fastening devices inserted in said openings.

Signed at New York city in the county of 35
New York, and State of New York this 27th
day of May, A. D. 1927.

RALPH G. PACKARD, Jr.
